UNITED STATES PATENT OFFICE.

LUIS AMEZAGA, OF FOREST HILLS, NEW YORK.

COMBINATION SANITARY BELT AND NAPKIN HOLDER.

Application filed March 22, 1927. Serial No. 177,437.

This invention relates generally to hygienic devices, and has more particular reference to a combination sanitary belt and napkin holder.

5 The invention has for an object, the provision of a combination sanitary belt and napkin holder, which is efficient and comfortable in action, and which offers the greatest possible amount of security to the wearer.

10 The invention has for a further object the provision of a combination sanitary belt and napkin holder which can be manufactured and sold at a reasonable cost.

15 For further comprehension of the invention and of the objects and advantages thereof, reference will be had to the following description and accompanying drawing and to the appended claim in which the various novel features of the invention are more 20 particularly set forth.

Referring to the accompanying drawing, forming a material part of this disclosure:

Fig. 1 is a perspective view of a device constructed according to this invention.

25 Fig. 2 is a vertical sectional view, taken on the line 2—2 of Figure 1.

Fig. 3 is a front view of the device.

Fig. 4 is a horizontal sectional view, taken on the line 4—4 of Figure 1.

30 Fig. 5 is a sectional view, taken on the line 5—5 of Figure 4.

Fig. 6 is a sectional view similar to Figure 5, but showing a modified form of the invention.

35 Fig. 7 is a sectional view, taken on the line 7—7 of Figure 8.

Fig. 8 is a fragmentary view similar to Figure 4 but showing a modification of the invention.

40 The reference numeral 10 indicates a resilient strap adapted to comfortably fit about the waist line of a wearer, and provided with a hook arrangement 11 for engaging the ends of the strap together. Depending from the

45 strap 10 is a back resilient strap 12, and a front resilient strap 13. The front resilient strap 13 is provided with a slide arrangement 14 to change the length thereof, and a hook 15 is engaged to the lower end of the

50 strap. The hook 15 engages a complementary element 16 fastened to the top of a trapezoidally shaped silk fabric joiner 17. The top end of another trapezoidally shaped silk fabric material joiner 18 is fastened to

55 the bottom of strap 12, while secured be-

tween the bottoms of the joiners 17 and 18 is a napkin holder 19. The sides 19' of the napkin holder are of curved contour adapted to snugly fit against the legs of a wearer, so as to afford comfort to the wearer and 60 freedom of movement. This napkin is made of liquid-proof material, preferably rubber.

Near the ends, and transversely of the napkin holder, are positioned certain holding straps 20 attached to the napkin holder at 65 their ends to allow a napkin indicated by dot dash lines 21', to be removably insertable therebeneath. Secured to the napkin holder 19 adjacent the joiner 18 are resilient leg straps 21 and 22, provided with slide arrangements 23 to change the lengths thereof, and hooks 24 are engaged to the ends of these straps. These hooks 24 are engageable with complementary elements 25 secured to the napkin holder 19 adjacent the joiner 17. 75

The curved contour sides 19' of the napkin are formed with inwardly projecting ends 19^a adapted to contact against the wearer, hiding the napkin from exterior view, and also holding the napkin firmly in place, removing possibilities of the napkin from sliding from the napkin holder and falling therefrom.

80 The modification illustrated in Figure 6 discloses a napkin holder 26 with inwardly projecting ends 27 vulcanized thereto.

85 The modification illustrated in Figures 7 and 8 discloses a napkin holder 28 with its edges bent upon itself, as at 29, and forced into a wedge shaped slot 30 of the ends 31 90 adapted to function similarly against the body of a wearer as the edges 19' function, that is, they contact against the wearer, hiding the napkin from exterior view, and also holding the napkin firmly in place. These 95 ends 31 are made of resilient material, and extensions 32 therefrom project over the resilient straps 20 aiding in the function of holding the napkin 21' in place.

100 Whenever desired, the hooks 24 and 15 may be disengaged from their complementary members to free the front portion of the napkin device.

105 While I have illustrated and described the preferred form, construction, and arrangement of the several elements employed, it will be understood that the device is nevertheless, susceptible of considerable modification thereon, and I therefore reserve the right and privilege of resorting to all such 110

changes as may be fairly embodied within the spirit and scope of the invention as claimed.

Having thus described my invention what I claim as new, and desire to secure by United States Letters Patent is:

A device of the class described, comprising a napkin holder sheet, means for secur-

ing a napkin thereto, the sides of the napkin holder sheet being bent upon themselves, and end strips of resilient material with wedge shaped slots forced on the bent sides, so as to stay thereon.

In testimony whereof I have affixed my signature.

LUIS AMEZAGA.
